United States Patent Office

Des. 206,921
Patented Feb. 7, 1967

206,921

DISPLAY STAND

Vernon L. Burchett, 5746 Mariposa Ave.,
Citrus Heights, Calif. 95610

Filed June 6, 1966, Ser. No. 2,585

Term of patent 14 years

(Cl. D80—10)

I claim:

The ornamental design for a display stand, as shown and described.
